UNITED STATES PATENT OFFICE

2,188,268

BRAKE HANGER BRACKET

David M. Light, Chicago, Ill., assignor to American Steel Foundries, Chicago, Ill., a corporation of New Jersey

Application November 14, 1938, Serial No. 240,209

13 Claims. (Cl. 188—209)

My invention relates to a brake hanger bracket for a railway car and more particularly to a novel arrangement for retaining a hanger in a brake hanger bracket and securing it against vibration.

It is a well known fact that wear on brake hangers and on the jaws of brake hanger brackets is principally due to vibration and not due to the normal wear which occurs between parts. 10 Because of this fact many designs of wear plates for brake hanger brackets have been evolved and numerous arrangements for securing the hangers within the brackets have also been devised. The object of my invention is to provide a novel arrangement which will close the brake hanger jaw and provide a substantial amount of wear metal beneath the top member of the hanger while at the same time providing that such wear will not result in chattering or looseness of the 20 parts.

Figure 1 is a side elevation of a brake hanger bracket embodying my invention. Figure 2 is a top plan view thereof, and Figure 3 is a sectional view in the vertical plane substantially 25 bisecting said jaw as indicated by the line 3—3 of Figure 2.

Describing the structure in more detail, the truck frame member 2 has the integrally formed brake hanger bracket 4 terminating in a jaw-like structure with the flaring top and bottom walls 6 and 7 and the substantially vertically arranged rib 8 joining said top wall 6 with said frame member 2. The said jaw structure has also the side walls 10 and 12, the forward edges 30 of which are of arcuate formation as indicated at 14, said lateral walls being relatively shallow and forming with the before-mentioned flaring top and bottom walls the pocket 16 at the rear of said jaw. On the bottom wall 7 may be seated my novel form of wear plate 18, said wear plate 40 comprising a hook-shaped rear portion 20 having a configuration to seat against the forward edges 14 of the lateral walls of said jaw. Said hook-like member 26 provides a seat as at 22 for the top member 24 of the loop-type brake hanger 45 26 of well known form. The forward portion of the wear plate 18 has clearance at the top as indicated at 28 from the flat U-shaped spring 30, said spring having a relatively long leg 31, the extreme inner end of which has bearing as 50 at 32 against the said top member 24 of the brake hanger, the other relatively short leg 33 of said U-shaped spring 30 overlying the top jaw 6 and having a central opening 34 aligned with other 55 openings 36 and 38 in the forward portions of

the top and bottom walls 6 and 7 of said jaw structure and with the relatively large opening 35 in the bottom leg of said spring and the opening 39 in the wear plate 18. Within said aligned openings may be received the securing bolt 40 5 the head of which is seated on the top leg 33 of the U-shaped spring 30 and the opposite end of which receives the threaded nuts 42, 42.

It will be apparent that after assembly of the parts, the U-shaped spring 30 by the bearing at 10 32 upon the top member of the brake hanger will prevent vibration of that member and of the wear plate 18 upon which the hanger is seated. The bottom surface of the said wear plate 18 has a configuration complementary to 15 that of the lower portion of the jaw structure and is seated thereupon. The retaining bolt 40 serves to secure all of said parts in position but in addition thereto the wear plate 18 has along its bottom edges the lateral flanges 44, 44 which 20 overlie the lateral edges of the bottom wall 7, thus adding further stability.

It will be seen that my novel arrangement substantially closes the open end of the jaw structure and affords compact and efficient arrangement of parts so cooperating that the tension of the U-shaped spring 30 is effective to hold all parts in secure and tight relationship with one another after the retaining bolt 40 has been secured in position.

It is to be understood that I do not wish to be limited by the exact embodiment of the device shown which is merely by way of illustration and not limitation as various and other forms of the device will, of course, be apparent to those 35 skilled in the art without departing from the spirit of the invention or the scope of the claims.

I claim:

1. In a railway car, a truck frame member having an integral brake hanger bracket comprising a jaw structure with flaring top and bottom walls and lateral walls terminating rearwardly of said top and bottom walls in arcuate edges, a wear plate seated upon said bottom wall and having a hook-like rear portion complementary in form to said arcuate edges and seated thereagainst, a loop-type hanger seated in said hook-like portion, a U-shaped resilient member having an arm overlying said top wall and an arm projecting into said jaw and bearing upon 50 said hanger, and securing means extending through said top and bottom walls, said wear plate, and said resilient member to retain said parts in operative assembly.

2. In a railway car, a truck frame member 55

having an integral brake hanger bracket comprising a jaw structure with flaring top and bottom walls and lateral walls terminating rearwardly of said top and bottom walls in arcuate edges, a wear plate seated upon said bottom wall and having a hook-like rear portion complementary in form to said arcuate edges and seated thereagainst, a loop-type hanger seated in said hook-like portion, a U-shaped resilient member 5 having an arm overlying said top wall and an arm projecting into said jaw and bearing upon said hanger, and securing means extending through said top and bottom walls through said wear plate and through both arms of said resilient member 10 means to retain said parts in assembled relationship.

3. In a railway car, a frame member having an integral brake hanger bracket terminating in a jaw structure with flaring top and bottom walls 20 and lateral walls having forward edges of arcuate formation, a wear plate seated on said bottom wall and having bearing against said forward edges, said wear plate having a hook-like rear portion forming a seat for a loop-type hanger, 25 a hanger seated therein, a U-shaped spring having the top leg thereof secured on said top wall and the bottom leg thereof having bearing on said hanger and being otherwise free of engagement, and retaining means for said parts in the 30 form of a bolt extending through said top and bottom walls, said wear plate, and both legs of said spring.

4. In a railway car, a frame member having an integral brake hanger bracket terminating in a 35 jaw structure with flaring top and bottom walls and lateral walls having forward edges of arcuate formation, a wear plate seated on said bottom wall and having bearing against said forward edges, said wear plate having a hook-like 40 rear portion forming a seat for a loop-type hanger, a hanger seated therein, a U-shaped spring having the top leg thereof secured on said top wall and the bottom leg thereof having bearing on said hanger and being otherwise free of 45 engagement, and retaining means for said parts in the form of a bolt extending through said top and bottom walls, said wear plate, and both legs of said spring, said U-shaped spring having a relatively short leg and a relatively long leg with 50 aligned openings therein, means for securing said relatively short leg in engagement with said top wall, said means extending through the opening in said bottom leg and having clearance therefrom, whereby said bottom leg may have free 55 bearing on said hanger.

5. A brake hanger bracket with flaring top and bottom walls and integral side walls having arcuate forward edges, a wear plate seated on said bottom wall and having lateral flanges overlying the edges of said bottom wall and rear portions complementary to and having bearing against said arcuate edges, said rear portion having a seat for a brake hanger, a loop-type hanger seated therein, a U-shaped spring having a top leg secured on said top wall and another leg extending within said jaw and spaced from said wear plate to have bearing on said hanger to urge said hanger downwardly, and retaining 60 means for said parts in the form of a securing bolt extending through aligned openings in said top and bottom walls, said top and bottom legs, and through said wear plate, said opening in said bottom leg having relatively large clearance from said securing bolt and from other 65

parts of said structure except for said bearing on said hanger to permit free movement thereof.

6. In a railway car, a frame member with an integral brake hanger bracket terminating in a jaw-like structure having flaring top and bottom walls and side walls with arcuate forward edges, a wear plate seated on said bottom wall and having a rear hook-like portion complementary in form to and having bearing against said forward edges, a loop-type hanger seated in said hook-like portion, a resilient member having a relatively short leg secured on said top wall and a relatively long leg extending over said wear plate but having clearance therefrom and having bearing on said hanger to urge said hanger downwardly and prevent vibration thereof, and means for securing said parts in assembled relationship in the form of a bolt extending through all of said parts but having clearance from said lower leg to permit free movement 10 thereof.

7. A brake hanger bracket having flaring top and bottom walls and receded lateral walls with arcuate forward edges forming with said top and bottom walls a pocket at the rear of said jaw, a wear plate seated on said bottom wall and having bearing against said arcuate edges, said wear plate having at its rear a seat for a brake hanger, a brake hanger seated therein, and a U-shaped spring having a relatively short leg secured on said top wall and a relatively long leg extending over said wear plate with clearance therefrom and bearing on said hanger to urge said hanger downwardly and means for securing said parts in assembled relationship, 20 said securing means comprising a retaining bolt extending through said top and bottom walls and having clearance from said relatively long leg whereby said leg may have unobstructed bearing against said hanger.

8. In a railway car, a frame member having an integral brake hanger bracket terminating in a jaw structure with flaring top and bottom walls and lateral walls having forward edges of arcuate formation, a wear plate seated on said bottom wall and having bearing against said forward edges, said wear plate having a hook-like rear portion forming a seat for a loop-type hanger, a hanger seated therein, a U-shaped spring, the top leg of which is seated on said top wall and bottom leg of which extends over said wear plate and has bearing on said hanger, and means for retaining said parts in assembled relationship, said retaining means comprising a bolt extending through aligned openings in said top and bottom walls, said wear plate, and both legs of said spring.

9. In a railway car, a frame member with an integral brake hanger bracket terminating in a jaw-like structure having flaring top and bottom walls and side walls with arcuate forward edges, a wear plate seated on said bottom wall and having a rear hook-like portion complementary in form to and having bearing against said forward edges, a loop-type hanger seated in said hook-like portion, a resilient member having a relatively short leg secured on said top wall and a relatively long leg extending over said wear plate but having clearance therefrom, the extremity of said long leg having bearing on said hanger to urge said hanger downwardly and prevent vibration thereof.

10. A brake hanger bracket having flaring top and bottom walls and receded lateral walls with arcuate forward edges forming with said top and bottom walls a pocket at the rear of said jaw, a wear plate seated on said bottom wall and having bearing against said arcuate edges, said wear plate having at its rear a seat for a brake hanger, a brake hanger seated therein, and a U-shaped spring having a relatively short leg secured on said top wall and a relatively long leg extending over said wear plate but having clearance therefrom and bearing on said hanger to urge said hanger downwardly and prevent vibration thereof.

bottom walls a pocket at the rear of said jaw, a wear plate seated on said bottom wall and having bearing against said arcuate edges, said wear plate having at its rear a seat for a brake hanger, 5 a brake hanger seated therein, and a U-shaped spring having a relatively short leg secured on said top wall and a relatively long leg extending over said wear plate with clearance therefrom and having bearing on said hanger to urge said 10 hanger downwardly, and means for securing said parts in assembled relationship, said means extending through said long leg but having clearance therefrom.

11. A brake hanger bracket with flaring top 15 and bottom walls and integral side walls having arcuate forward edges, a wear plate seated on said bottom wall and having lateral flanges overlying the edges of said bottom wall and rear portions complementary to and having bearing 20 against said arcuate edges, said rear portion having a seat for a brake hanger, a loop-type hanger seated therein, and a U-shaped spring having a top leg secured on said top wall and another leg extending within said jaw and spaced from 25 said wear plate and from other parts of said structure to have free bearing on said hanger to urge said hanger downwardly.

12. A brake hanger bracket having flaring top and bottom walls and recessed lateral walls with 30 arcuate forward edges forming with said top and bottom walls a pocket at the rear of said jaw, a

wear plate seated on said bottom wall and having bearing against said arcuate edges, said wear plate having at its rear a seat for a brake hanger, a brake hanger seated therein and resilient means secured against said top wall and having bearing on said hanger to urge said hanger downwardly, said resilient means having clearance from other parts of said structure between its point of securement against said top wall and its bearing on said hanger to afford 10 freedom of movement, and means for securing said parts in assembled relationship.

13. In a railway car, a frame member having an integral brake hanger bracket terminating in a jaw structure with flaring top and bottom walls 15 and lateral walls having forward edges of arcuate formation, a wear plate seated on said bottom wall and having bearing against said forward edges, said wear plate having a hook-like rear portion forming a seat for a loop-type hanger, a hanger seated therein, a U-shaped spring, the top leg of which is seated on said top wall and bottom leg of which has bearing on said hanger, and means for retaining said parts in assembled 20 relationship, said bottom leg extending over said wear plate but having clearance therefrom and from all other parts of said structure between said point of bearing on said hanger and said point of securement on said top wall.

DAVID M. LIGHT.
